UNITED STATES PATENT OFFICE.

STEPHEN EVANS ALLEY, OF GLASGOW, SCOTLAND, AND ROBERT McGREGOR, OF LONDON, ENGLAND.

CRANK-CASE.

1,098,341.

Specification of Letters Patent.

Patented May 26, 1914.

Application filed May 13, 1913. Serial No. 767,429.

To all whom it may concern:

Be it known that we, STEPHEN EVANS ALLEY and ROBERT McGREGOR, subjects of the King of Great Britain and Ireland, and residents, respectively, of Glasgow, Scotland, and London, England, have invented certain new and useful Improvements in Crank-Cases, of which the following is the specification.

10 The invention has for its object to provide for vertical inclosed reciprocating engines, compressors, pumps and the like, a single-piece crank-case forming a base, receiving the crank shaft bearings, and forming also an entablature to receive the cylinders or distance piece trunks; the structure being of much better continuity of strength than hitherto usual, and permitting of easy assembly and withdrawal of the crank and 20 of the provision of unusually large inspection doors.

As illustrated in longitudinal section, in sectional end elevation, and in plan in Figures 1, 2 and 3 respectively on an accompanying sheet of explanatory drawings, a crank-case made according to the invention is as a whole of prismatic form, that is to say, it is rectangular in plan with substantially vertical ends A and with sides B sloping inwardly upward. It is formed with a gap C centrally along the flat top and the ends to about the level of the bearings of the crank shaft D, thus allowing the crank shaft to be lifted vertically from its 30 bearings and through the crown of the crank case. The seatings E for the lower halves of the crank shaft end bearings are formed upon the end plates contiguously to the gaps—the upper halves F are secured in usual manner upon them.

The seatings G for the lower halves of the intermediate bearing are supported upon deep webs H extending up from the base and extending out to the sides and top—in 45 fact, webs somewhat similar in contour to the end plates. These vertical webs are reinforced at convenient intervals by webs J at right angles to them, and the outermost of which extend to and reinforce the

end plates A. A bearer plate K having 50 transverse webs L contiguous to the connecting rod and other apertures is applied to the top plate to receive the cylinders or distance trunks. The gaps in the ends of the case are closed by cover plates applied 55 to seatings M on the ends. Large inspection apertures N fitted with a door or doors (not shown) are provided along the sides between the crank-bearings webs.

It is obvious that the details of the crank 60 case may be varied in a minor degree—for example, the position of the various webs and apertures and the particular angle of the sides of the case.

What we claim is:—

65 A one-piece crank case of prismatic form with base flanges apertured to receive securing bolts, said case being gapped along its top and down its ends to permit of the vertical removal of the crank shaft, inwardly extending arcuate flanges at the bottoms of the end gaps to form seatings for the crank shaft end bearings and apertured within the casing to receive securing bolts 70 for the end bearings, end cover plates to 75 close the bearing gaps in the ends of the casing, deep webs intermediate the end plates and approximating the same in contour, arcuate flanges thereon forming seatings for intermediate bearings, reinforcing 80 longitudinal webbing supporting said intermediate webs and end plates, a flat bearer plate on the top of said casing apertured 85 to permit the passage therethrough of connections to the crank shaft, the side walls of the casing being apertured to afford inspection apertures, substantially as described.

90 In testimony whereof we have signed our names to this specification, in the presence of subscribing witnesses.

STEPHEN EVANS ALLEY.
ROBERT McGREGOR.
